UNITED STATES PATENT OFFICE.

ELI D. BEARD, OF SODA SPRINGS, IDAHO.

TENT.

1,253,123.

Specification of Letters Patent.

Patented Jan. 8, 1918.

Application filed July 20, 1917. Serial No. 181,889.

To all whom it may concern:

Be it known that I, ELI D. BEARD, a citizen of the United States, residing at Soda Springs, in the county of Bannock, and State of Idaho, have invented new and useful Improvements in Tents, of which the following is a specification.

This invention relates to tents and comprehends the provision of a tent of improved construction, which may be easily and quickly set up by one person and which when not in use as a tent may be folded into very compact form to facilitate transportation and to economize space in storing.

A further object of the invention is to provide a very strong and substantial tent which may be tightly closed at its bottom and entrance opening to exclude wind, rain, small animals and the like.

The invention also aims to generally improve tents to render them more useful, convenient and commercially desirable.

With these and other objects in view as will become more apparent as the description proceeds, the invention consists in certain novel features of construction, combination and arrangement of parts as will be hereinafter fully described, illustrated and claimed.

In the drawings,

Figure 1 is a perspective view of the tent showing the entrance opening therein.

Fig. 2 is a transverse sectional view through the tent.

Fig. 3 is a fragmentary horizontal sectional view.

Fig. 4 is an enlarged detail view of the pole joint.

Fig. 5 is a similar view showing the joint collapsed.

Referring in detail to the drawings by numerals, 1 designates as an entirety, my improved tent having the inclined top walls 2, rear wall 3 and front 4. The top walls are joined along their longitudinal lower side edges to side walls 5 which are connected by rings 6 to pins 7 adapted to be driven into the ground to anchor the lower edges of the side walls in close relation thereto. The lower edges of the rear wall and front closing flaps may also be provided with rings 6 and pins 7 if desired. The rings extend through the canvas forming the tent which is reinforced so as not to tear away from the rings and the pins are provided with holes to accommodate the rings.

The front 4 comprises the flaps 8 and 9. The flap 8 overlies a portion of the outer face of the flap 9 and may be secured in closed position by snap hooks 10 which are carried by the edge of the snap hook and which are engageable in rings 11 secured between the flap 9. As a further securing means, I provide the vertical edge of the flap 9 with a series of snap hooks 12 which may be engaged with rings 13 secured to the inner side of the flap 8.

Each side wall 5 is provided with a bottom flap 14, the rear wall is provided with a bottom flap 15 and the front wall sections are provided with the bottom flaps 16. These flaps, when the tent is set up, are adapted to extend at right angles to their walls and lie in close contact with the ground, thus forming all around the tent an interior bottom extension which will assist in excluding wind, rain and other elements from the tent. When desired, these bottom flaps or sections may be secured in raised position against the walls to which they are attached by snap hooks 17 carried by the flaps and rings 18 carried by the walls of the tent. The hooks are positioned at the ends of the flaps and each ring is so positioned as to be engaged by a pair of hooks so as to be positioned in the ends of the flaps and thus economy in hooks and rings is secured.

The poles 19 support the top of the tent in a raised position. Each pole is provided on its upper terminal with a ring or loop 20 which is connected to a ring 21 secured to the apical edge of the tent adjacent one end thereof. The rings 20 and 21 may be united by a snap hook 22 to which is secured a stay rope 23 which is connected by a snap hook 24 and ring 25 to a pin 26. The rope is looped through the eye 27 of the snap hook and may be tensioned by the member 28 as shown.

Each pole is formed in two sections, an upper section 28' and a lower section 29. The lower section 29 is provided on its upper end with a dowel or pin 30 which is receivable in a socket 31 in the upper section 28'. The sections are held in alinement by a coupling comprising a pair of plates 32 secured to opposite sides of the section 29 and a pair of plates 33 secured to opposite sides of the section 28'. Each plate 32 has an arcuate slot 34 which terminates at its lower end in a reduced straight portion 35 and each plate 33 is formed with a tongue

36 adapted to slide into the reduced straight portion 35 of one of the slots 34 and be held against rotation thereby. When it is desired to fold the pole, it is only necessary to raise the upper section to disengage the pin 30 from the socket 31 and then move the tongues 36 into the curved portions of the slot and fold the pole sections together.

A ridge rope 37 extends along the interior 10 of the tent adjacent the apical edge thereof and is secured at its ends to the rings 21. This rope, besides acting as a reinforcement provides a convenient support for clothes hangers. The tent may also, if desired, be 15 provided with a pocket to receive various articles and may have as part of its equipment a mirror. Other articles which will contribute to the pleasure or comfort of the occupants may also be used. The tent, as 20 will be clearly understood, may be set up over a boat at which time the end snaps could be snapped into rings provided in the end of the boat and the side snaps into rings on the side of the boat.

25 From the foregoing description, taken in connection with the accompanying drawings, it will be evident that I have provided a very practical, substantial and convenient tent, which may be quickly set up or taken 30 down and which may be folded into very compact form.

While I have shown and described the

preferred embodiments of my invention, it will be clearly understood that I do not wish to be limited to this construction, but may 35 make such changes as will fall within the scope and spirit of the invention as claimed.

What I claim is:

1. In a tent, vertical walls, bottom flaps 40 permanently secured to said walls and normally disposed at right angles thereto within the tent in engagement with the ground and means for securing said flaps in parallelism with and against the walls to which they are attached.

2. In a tent, vertical walls, bottom flaps 45 secured to the lower edges of said walls to lie in contact with the ground, snap hooks carried by said bottom flaps and rings carried by the walls to which said snap hooks 50 may be engaged to hold the bottom flaps in raised position.

3. In a tent, vertical walls, means secured 55 to said walls for holding them in close engagement with the ground, bottom flaps secured to said walls and normally disposed at right angles thereto in contact with the ground within the tent, and coöperating means carried by the respective parts for securing said bottom flaps in parallelism 60 with and against said vertical walls.

In testimony whereof I affix my signature.

ELI D. BEARD.
